US00D927453S

(12) **United States Design Patent** (10) **Patent No.:** **US D927,453 S**
(45) **Date of Patent:** **** Aug. 10, 2021**

(54) **HEADPHONES**

(71) Applicant: **Apple Inc.**, Cupertino, CA (US)

(72) Inventors: **Christina J. Smiechowski**, West Hollywood, CA (US); **Carlos M. Santana**, Granada Hills, CA (US); **Kevin P. Blasko**, Santa Monica, CA (US); **Guillaume Raoult**, San Francisco, CA (US); **Christopher Kuh**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/755,092**

(22) Filed: **Oct. 16, 2020**

Related U.S. Application Data

(63) Continuation of application No. 29/691,340, filed on May 15, 2019, now Pat. No. Des. 899,401.

(57) **CLAIM**

The ornamental design for headphones, as shown and described.

DESCRIPTION

FIG. 1 is a top front perspective view of headphones showing the claimed design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the headphones that form no part of the claimed design.

The dot-dash broken lines in the figures show boundaries that form no part of the claimed design.

1 Claim, 6 Drawing Sheets
